UNITED STATES PATENT OFFICE.

WILLIAM GOERTZ, OF BROOKLYN, NEW YORK.

MACHINE-CENTER AND THE LIKE.

1,279,534.

Specification of Letters Patent. Patented Sept. 24, 1918.

Application filed May 19, 1916. Serial No. 98,530.

To all whom it may concern:

Be it known that I, WILLIAM GOERTZ, a citizen of the United States, residing at Brooklyn, in the county of Kings and State 5 of New York, have invented certain new and useful Improvements in Machine-Centers and the like, of which the following is a specification.

This invention relates more especially to 10 work-supporting centers for lathes and other machines which embody spindles which engage the pieces to be worked, at points lying within the axes of said spindles. More specific objects of invention will appear in 15 the specification and be pointed out in the appended claim, reference being had to the accompanying drawings which show a preferred embodiment of my invention.

In the drawings:

20 Figure 1 is a combined side elevation and axial section of a machine center embodying my improvements;

Fig. 2 is a transverse section on the line 2—2, Fig. 1.

25 In the art to which the present invention appertains, it has long been customary to make lathe centers of machinery steel, sometimes case hardened to enable it to better withstand hard wear, or of tempered tool 30 steel which possesses higher wearing qualities. In modern machine shop practice, it has become imperative to employ high speeds to large work as well as small. One of the developments of these requirements 35 has been the so-called "high-speed" steels which embody certain ingredients including tungsten, and which are extremely tough. Such steels are moreover very expensive. When a piece of machinery steel is case-hardened or a piece of tool steel is hardened 40 and tempered, it is liable to become warped, even when proper care is exercised in the operation. This defect is peculiarly undesirable in tapered bodies although it may 45 be overcome by an expensive grinding oper-

ation. According to my invention, however, an outer tapered body portion 1 is provided with an axial bore or hollow which extends for a considerable part of the length of said body portion. Said central bore is adapted 50 to receive a core 2 which preferably fits therein with a driving fit and which may be provided with a flat inner end to abut squarely against the flat inner end of the bore in the body portion 1. The outer end 55 of the core 2 is provided with a conical point 3 for constituting the effective work-supporting machine center. If desired, the outer body portion 1 may be provided with a flange 4 to make it easier to insert the center 60 into a spindle and to remove it therefrom. The outer end of said body portion may be conically tapered at 5 to correspond to the taper of the center core. It will be understood that my construction makes it 65 possible to construct the outer tapered body of relatively soft stock which requires neither case hardening nor tempering while permitting the essential wear resisting part of the center to be made of a relatively small 70 piece of stock of uniform cross-section which may be more readily manipulated for hardening, tempering and grinding, requires no taper, and which especially in the case of the so-called "high speed" steels involves a 75 great saving in the first cost of production.

I claim:

80 A machine center or the like, comprising an outer tapered body of machinery steel provided with a cylindrical hollow extending a portion of its length, and a cylindrical bar of high speed steel abutting at one end against the inner end of said hollow and having its other end projecting, the projecting end of said cylindrical bar and the circum-adjacent portions of the outer body portion being provided with an unbroken surface suitably formed to provide a work-centering point.

WILLIAM GOERTZ.
